O. MESSTER

APPARATUS FOR PRACTICING SIGHTING AND DETERMINING PHOTOGRAPHICALLY
THE DEVIATION ERRORS
Filed May 29, 1919

Inventor

Oskar Messter

*By William C. Linton
A.T.C.*

UNITED STATES PATENT OFFICE.

OSKAR MESSTER, OF BERLIN, GERMANY, ASSIGNOR TO N. V. AEROFOTO, OF AMSTERDAM, NETHERLANDS, A FIRM.

APPARATUS FOR PRACTICING SIGHTING AND DETERMINING PHOTOGRAPHICALLY THE DEVIATION ERRORS.

Application filed May 29, 1919. Serial No. 300,766.

(GRANTED UNDER THE PROVISIONS OF THE ACT OF MARCH 3, 1921, 41 STAT. L., 1313.)

To all whom it may concern:

Be it known that I, OSKAR MESSTER, manufacturer, a citizen of the German Republic, and residing at Berlin, Nos. 110-111 5 Leipzigstrasse, in the German Republic, have invented certain new and useful Improvements in Apparatus for Practicing Sighting and Determining Photographically the Deviation Errors (for which I have 10 made application for patent in Germany July 17, 1916, October 5, 1916, April 12, 1917; Austria, March 18, 1917; Denmark, January 23, 1919; Sweden, January 23, 1919; Netherlands, January 24, 1919; Hungary, January 27, 1919; and Switzerland, 15 Aug. 16, 1919), of which the following is a specification.

This invention relates in general to an apparatus for practicing aiming in the car of a flying machine and for determining photographically the deviation errors made in firing at another flying-machine; in particular the invention relates to means whereby the deviation errors of the operator of a machine 20 gun mounted upon the car of a flying machine may be determined, in an apparent air-fight, for each shot fired by the practicing persons. By the term firing I do not mean actual firing but merely operating the 25 trigger of the device hereinafter described. For that purpose the apparatus in question is constructed similar to an apparatus for taking photographic pictures, especially a so-called series picture-apparatus, and that 30 apparatus is employed in lieu of the machine gun, but at the same place where this gun, when practically employed, is mounted in the car of the flying machine, and it serves to ascertain the quickness in the succession 35 of the shots produced, in an air-fight, by a machine gun. The photographic apparatus for taking the pictures may be a kinematographic apparatus, the wheel-work of 40 which is driven either by a spring-work that normally is checked, or by an electromotor, and a thread-cross is arranged in the field 45 of view of that apparatus, and a contrivance for taking aim similar to that used in connection with machine-guns is arranged 50 parallelly to the optical axis. This apparatus is operated by means of a small lever resem-

bling the trigger of a gun, and as long as the lever or trigger is actuated kinematographic pictures are taken showing the quickness of the succession of the shots of a machine 55 gun.

Means are provided by which may be seen which of the two flyers that are occupied in an exercising "fight" and are "fighting" with each other has first sighted the apparatus correctly, so that the superiority of one or the other of them may be ascertained.

In order to make my invention more clear, I refer to the accompanying drawing, in which is shown a longitudinal section 65 through an apparatus constructed according to my invention. Referring to said figure, *a* is the apparatus for taking photographic pictures which is constructed similar to a kinematographic apparatus; *b* is the contrivance for taking aim which resembles that of a machine gun and is arranged parallelly to the optical axis of the kinematographic apparatus; *c* is a small electromotor, which may be inserted into the circuit by a 70 lever or trigger *d* closing a switch *s*. When the motor *c* is running, the filmband *e* is moved, by the mediation of known means, in regular intervals corresponding to the quickness in the succession of the shots of a 75 machine gun.

Near to the picture window *h* is a double-armed lever *f* fulcrumed at *j*; the upper arm of said lever is held in contact with the film-band by a bolt *i* which is under spring-pressure. Of course, an equivalent means may be employed for pressing the lever *f* against the film band. The other arm of the lever *f* is in contact with a spring *g* forming part of the circuit containing the electromotor *c*. The electric source of current is carried, as usually, in the car of the flying machines, and wires connect it with the apparatus in question. The film band forms a support for the upper arm of the lever *f* so long as it is pulled by the roller *n* off the roller *m*, but when the end of the film band leaves the roller *m*, it can no more act as a support for the lever, in consequence of which the bolt *i* forces the lower arm of the lever off the 90 spring *g* when the contact between the parts *f* and *g*, and thus also the circuit, will be 95 100

broken so that the electromotor stops, and remains at rest, when the trigger *d* is again actuated this operation again occurs.

The dial and the hands of a time-piece 5 (not shown) situated at an appropriate place of the apparatus are arranged in the picture field of the latter, the object of this arrangement being to allow of seeing which of the two "fighting" flyers has first sighted his apparatus correctly. The pictures taken allow 10 of ascertaining how the exercising fight proceeded, at which place or places the apparatus has been sighted, how often the flyers have not sighted the apparatus correctly, 15 and finally, considering also the space of time, as recorded, which of the two flyers is to be considered as victorious.

Having now described my invention, what I desire to secure by a patent of the United 20 States is:

An apparatus for practicing sighting and determining photographically the deviation errors comprising a cylindrical casing having end walls closing said casing and representing in contour a machine gun, a handle 25

provided at one end wall of said casing, a photographic apparatus arranged within said casing and including a lens carried by the other end wall of the casing, a strip film feeding mechanism arranged within said casing, an electric motor for actuating said film feeding mechanism, an electric circuit in which is included said motor, a switch arranged within said casing and included in said electric circuit, a trigger arranged adjacent said handle and operatively connected to said switch, a circuit breaker carried by said casing and included in said electric circuit, said circuit breaker comprising a spring pressed lever, a roller carried by said lever and adapted to rest upon said film strip whereby the circuit breaker will be kept closed and sighting means arranged upon said casing parallel with the optical axis of said photographic apparatus where- 40 by a series of pictures may be taken to ascertain whether the apparatus has been sighted correctly.

In testimony whereof I affix my signature.
OSKAR MÈSSTER.
